UNITED STATES PATENT OFFICE.

NEWELL A. HONEYWELL AND CHARLES O. MCKAIG, OF INGLEWOOD, CALIFORNIA.

IGNITION AND STARTER CONTROL FOR AUTOMOBILES.

1,309,135.

Specification of Letters Patent.

Patented July 8, 1919.

Application filed February 13, 1918. Serial No. 216,985.

To all whom it may concern:

Be it known that we, NEWELL A. HONEYWELL and CHARLES O. MCKAIG, both citizens of the United States, residing at Inglewood, in the county of Los Angeles and State of California, have invented a new and useful Ignition and Starter Control for Automobiles, of which the following is a specification.

10 Our invention relates to a device for controlling the opening and closing of switches in the ignition and starter circuits commonly used on automobiles, being more particularly a lock and controlling device for 15 starting an automobile.

One of the principal objects of our invention is to produce a control of the class described, of simple form and construction, wherein a lock is operated by a suitable key, 20 the key serving as an operating member for closing the ignition and starter circuits.

Another object of our invention is to produce a control of the class described, of simple form and construction, wherein a single 25 key is used for operating the device, which key has a limited rotary movement, and in addition thereto, a longitudinal movement for the purpose of operating switches.

Other objects and advantages will be 30 made evident hereinafter from the following specification.

Referring to the drawings, which are for 35 illustrative purposes only,

Figure 1 is a diagrammatic sectional view 40 of the dash and floor of an automobile showing a device embodying our invention mounted thereon.

Fig. 2 is a sectional plan view of the device shown in Fig. 1.

Fig. 3 is a rear elevation of the device 45 shown in Fig. 2, the back of the device being removed.

Fig. 4 is a vertical sectional view on line 4-4 of Fig. 3.

Fig. 5 is a face view of the lock.

Fig. 6 is a fragmentary sectional plan view of a portion of the device.

Fig. 7 is a diagrammatic wiring view.

Fig. 8 is a perspective view of the key.

50 Fig. 11 designates a box, open at the back, and having extensions or ears 12 at each side adapted to be secured in any suitable manner to the under side of the dash 13 of an automobile. 15 designates a lock cylinder formed on the box 11 and extending for

wardly therefrom, the lock cylinder having slidably mounted therein a rotatable barrel 16 slotted longitudinally, as indicated at 17, to receive a key 18. 20 designates a series of tumblers mounted in the barrel 16, 60 and 21 designates a series of followers mounted in the cylinder 15, which followers are elastically held in outward position by means of a series of coiled springs 22, the said springs 22 and followers 21 being retained in the cylinder 15 by means of a flat ring 23 on the cylinder 15, held thereon by means of a suitable screw 24.

The barrel 16 is provided at its inner end with a head 25 and a circular flange 25' 70 which abuts against the inner face of the box 11. 26 designates a circular groove which is engaged by a plate 27 secured by suitable screws 28 to the box 11. A portion of the flange 25' is cut away as indicated 75 at 29 in Fig. 3, so that when the barrel is turned, as hereinafter described, the barrel is free to move inwardly, the cut away portion 29 of the flange permitting the flange 25' to pass the plate 27. The turning move- 80 ment of the barrel 16 is limited by means of pins or stops 31 and 32 which are mounted in the box 11, extending inwardly therefrom into the path of a contact blade 33 mounted on the head 25 of the barrel. 85

35 designates a contact plate mounted on a block 36 of insulating material on the inside of the box 11, a suitable binding post 37 extending through the plate 35 and the lower wall of the box 11 to the interior 90 thereof where a suitable electrical connection 39 is made to the ignition circuit 40, hereinafter referred to.

42 designates a plate or cover for the back of the box 11, said plate being made of insulating material and having mounted thereon a contact block 43 in axial alinement with the barrel 16 heretofore referred to. 44 designates a post on the contact 43, which extends through the plate 42 to the exterior 95 thereof, the post 44 being provided with a suitable electrical connection 45 to the motor circuit 46 hereinafter referred to. 48 designates a post mounted in the back plate 42, a reduced portion 49 of the post extending 100 through the plate 42 to which is made a suitable electrical connection 50 to the battery circuit 51 hereinafter referred to. 105

Mounted on the post 48, by means of a suitable screw 53, is a spring arm 54 which 110

extends into the path of the head 25 on the barrel 16, the arm 54 having a contact block 55 mounted thereon arranged to contact with the block 43 when the barrel 16 is moved inwardly as hereinafter described, the arm 54 and contact 55 thereon being normally in the position shown in Fig. 2 of the drawings.

The key 18 is made with a notched blade 60 formed on a shank 61 which terminates in an enlarged head or button 62.

In Fig. 7 we have shown the invention connected to the electrical circuits commonly found on an automobile, and have diagrammatically shown elements in said circuits which consist of a distributor 70, a motor 71 and a battery 72.

The device is operated in the following manner:

Assuming the parts to be in the position shown in Figs. 2 and 7, in which position both the ignition circuit and starting circuit are open, and it is desired to start the automobile the blade 60 of the key is inserted in the slot 17 in the barrel 16, as shown in Fig. 4, the proper notches in the blade registering with the proper tumblers and moving the tumblers and followers so that the barrel is free to turn in the cylinder 15. The key is then turned which brings the blade 33 on the barrel 16 from the full line to the dotted line position shown in Fig. 3, the further rotary movement of the barrel being limited by the stop 32, and when in such dotted line position, the blade 33 engaged the contact plate 35 thereby closing the ignition circuit, the barrel 16, being at all times connected with the battery 72 through the arm 54, post 48, connection 50 and battery circuit 51.

When the barrel 16 has been moved as just described, the cut away portion of the flange 25' is in such a position as to permit the barrel to move past the plate 27. This is done by pressing the foot against the head 62 of the key, the shank 61 of the key being of the same diameter as the barrel. The barrel may be pushed forwardly, the shank of the key entering the cylinder 15. The inward movement of the barrel 16 moves the arm 54 and contact block 55 into con-

tact with the block 43 thereby closing the starter circuit through electrical connection 45 and the motor circuit 46. Upon release of the pressure of the foot against the key the spring arm 54 returns the barrel to its original position thereby breaking the motor circuit through the blocks 43 and 45 so that the motor circuit is only closed when the key is pressed inwardly as above described. It is understood that the key remains in place in the barrel 16 and the barrel 16 is left in the dotted line position shown in Fig. 3, in which position the ignition circuit remains closed until the removal of the key. It is to be noted that the starting motor cannot be connected until the ignition circuit has been closed and the key cannot be removed without breaking the ignition circuit.

We claim as our invention:

1. An ignition and starter control for automobiles comprising a primary or ignition switch, a secondary or starter switch, a lock, an operating member rotatably and slidably mounted in the lock, and means for preventing longitudinal movement of said member during its rotatable movement, said rotatable movement of the member closing the primary switch and the longitudinal movement closing the secondary switch.

2. An ignition and starter control for automobiles comprising a box, a lock on said box, a rotatable and slideable barrel in said lock, a contact blade carried on the barrel, a contact in said box adapted to be engaged by said blade during the rotation of said barrel, engaging means for preventing longitudinal movement of the barrel during its rotation, an elastically mounted contact in engagement with said barrel, a starter contact in said box adapted to be engaged by the elastically mounted contact when said barrel is moved longitudinally, and a removable operating key for said lock.

In testimony whereof, we have hereunto set our hands at Los Angeles, California, this 6th day of February, 1918.

NEWELL A. HONEYWELL
CHARLES O. MCKAIG.
